UNITED STATES PATENT OFFICE.

ROY D. KING, OF CHICAGO, ILLINOIS, ASSIGNOR TO COIN CONTROLLED LOCK COMPANY,
OF CHICAGO, ILLINOIS, A CORPORATION OF CALIFORNIA.

LOCK-GUARD.

1,310,834.

Specification of Letters Patent. Patented July 22, 1919.

Original application filed June 2, 1916, Serial No. 101,212. Divided and this application filed May 8, 1918.
Serial No. 233,381.

To all whom it may concern:

Be it known that I, Roy D. King, a citizen of the United States, residing at Chicago, in the county of Cook and State of Illinois, have invented certain new and useful Improvements in Lock-Guards, of which the following is a specification.

This invention, a division of my application Serial No. 101,212, filed June 2, 1916 for improvements in coin controlled locks, relates to means for preventing accidental unlocking of a lock until the key has been withdrawn and reinserted in the lock.

My improvements, generally applicable to cylinder or tumbler locks, are at present exemplified in a coin-controlled lock of the character described in my application mentioned above. These locks are used on parcel lockers and in similar places where it is necessary to deposit a coin in the lock before the same can be operated, the key being withdrawn and carried by the user as his check until such time as he desires to reopen the locker or container.

It sometimes happens in locks of this general character that the user after locking the lock will, before removing the key, accidentally unlock it again. Since the coin which was utilized to effect the locking of the lock has been ejected at the completion of the locking movement, it is obvious that the use of this coin has been lost and the customer must deposit another coin in order to lock it again. With a view to obviating this difficulty and insuring the user against the loss of his coin by accidental unlocking of the lock, I have provided as the primary object of my invention, an improved "fool-proof" device, which prevents unlocking of the lock until the key has been withdrawn and re-inserted therein.

I have also aimed to provide a device of this character comprising but very few parts designed so that they may be compactly arranged in a lock and will positively and effectually serve the purposes desired.

Other objects and attendant advantages of my invention will be readily appreciated as the same is better understood by reference to the following description when considered in connection with the accompanying drawings, in which—

Figure 1 is a rear elevation of a lock em-

bodiment of my invention, showing the parts in normal unlocked position and omitting the coin-controlled mechanism described and claimed in my application mentioned above;

Fig. 2, a sectional view taken substantially on the line 2—2 of Fig. 1;

Fig. 3, a rear elevation of the lock with the key cylinder moved to locked position, certain of the parts being removed or broken away to more clearly show the parts behind; and

Fig. 4, a similar view showing the position which the parts assume after the key has been withdrawn and re-inserted.

Since this application pertains simply to the means for preventing unlocking of the lock until after the key has been withdrawn and re-inserted, I have illustrated in the drawings and will describe the construction and operation of only such parts of a lock as are necessary for a clear understanding of the present invention. The parts which may be of any suitable or preferred construction comprises a front or case designated generally by reference character 5, to the rear face of which is suitably secured a housing or frame 6 forming a bearing support for the key-cylinder 7. This cylinder, equipped with an arm 8 connected with a locking bolt 9 is adapted to be oscillated to project and retract the bolt by operation of a key 11 inserted in the key way 12 and engageable with the tumblers 13, as is well understood in this art. The normal unlocked position of the parts is as shown in Fig. 1, from which it will be readily seen that upon oscillating the key cylinder in a counter-clockwise direction the locking bolt will be projected as shown in Fig. 3, and the lock locked by the action of the tumblers.

My improved device for preventing unlocking of the lock until the key has been withdrawn and re-inserted, comprises generally speaking, a pawl adapted, under certain conditions, to engage with an abutment carried by the key cylinder and prevent unlocking movement of the same. This pawl, which is designated generally by reference character 14, comprises a body portion provided with an elongated slot 15, a tail portion 16, and a finger or beveled end 17 adapted to engage with an abutment or shoulder 18 carried by an arm 19 rigidly attached to the key-cylinder. The pawl is mounted upon

a pin 21 which extends through the slot 15 so that the pawl is pivotally supported upon said pin and is also slidably relatively thereto. When the lock is in unlocked position 5 the pawl is normally held in the position shown in Fig. 1 by a small spring 22 coiled upon the pin 23 and having an end projecting laterally therefrom through an opening 24 in the pawl, this spring being adapted to 10 normally depress the rear end of this pawl so that the pawl assumes the position shown in Fig. 1, as previously stated. The tail 17 of the pawl projects downwardly through a slot in the key-cylinder into the path of the 15 key 11 when positioned in the cylinder. Assuming that the lock is in unlocked position with the parts disposed as shown in Fig. 1; when the lock is locked by turning the key in a counter-clockwise direction, viewing this 20 figure, and after the deposit of a coin, as explained in my application mentioned above, the shank of the key engages the tail 16 and moves the pawl on its pivot into the position shown in full lines in Fig. 3, in which position 25 the end 17 is disposed beneath the abutment 18 so that reverse rotation of the key-cylinder is prevented. The lock cannot be unlocked until the key has been withdrawn and re-inserted to release the pawl. When 30 the key is withdrawn the pawl will be rocked on its pivot by the spring 22 into the position shown in dotted lines in Fig. 3, the end 17 of the pawl being now in the path of the auxiliary abutment 25 formed integral with the 35 arm 19, so that the pawl and this abutment act, in addition to the tumblers, as a preventive against unlocking the lock. This construction insures a complete stroke upon the locking movement before the unlocking 40 movement can take place. It will be observed from the position of the pawl 14, shown in dotted lines in Fig. 3, that when the key has been withdrawn the tail 16 lies directly across the key-way opening so that 45 it will be engaged by the key when it is inserted. The re-insertion of the key therefore lifts the pawl from the position shown in dotted lines in Fig. 3 to the position shown in Fig. 4, thereby withdrawing the 50 end 17 from the path of travel of the abutment 25 so that the lock can be turned to unlocked position, whereupon the pawl will reassume its original position, as shown in Fig. 1.

55 It is believed that my invention, its mode of operation and many of its advantages will be understood from the foregoing without further description, but it should be obvious that the details of construction illustrated 60 and described may be varied within considerable limits without departing from the spirit of the invention as set forth in the following claims.

65 I claim:

1. In a lock, the combination of a key-

cylinder, an abutment projecting laterally from said cylinder, a yieldingly mounted pawl having a tail normally disposed in the path of a key inserted in said cylinder and a tooth adapted to engage said abutment, and a spring controlling said pawl so that when the key-cylinder is moved to locked position said pawl will be disposed in the path of travel of said abutment to prevent unlocking of the lock prior to withdrawal 75 of the key, the pawl being adapted to be moved transversely of the cylinder from operative position by the insertion of a key in said cylinder.

2. In a lock, the combination of a key-cylinder provided with a laterally projecting abutment, and means including a pivotally mounted pawl disposed transversely of said cylinder for engaging said abutment to retain said cylinder in locked position before the key is withdrawn, said means being adapted to be released from said abutment by the insertion of a key in said cylinder.

3. In a lock, the combination of a key-cylinder provided with an abutment, a fixed pivot pin, a pawl pivotally and slidably mounted upon said pin, and a spring acting on said pawl to normally maintain the same in inoperative position, said pawl being movable into co-operative relation with said abutment by a key in said cylinder when the cylinder is turned to locked position and being movable out of co-operative relation with said pawl by said key when the key is re-inserted in the cylinder.

4. In a lock, the combination of a key-cylinder having a part adapted to be engaged to prevent unlocking movement of the cylinder, and a member normally disposed in the path of movement of a key inserted in the cylinder and adapted to be moved by the key upon rotation thereof, into engagement with said cylinder part so as to prevent unlocking movement of said cylinder.

5. In a lock, the combination of a key-cylinder having a part adapted to be engaged for preventing unlocking movement of the cylinder, and a member normally disposed in the path of a key inserted in the cylinder and adapted to be moved by the key upon locking movement thereof so as to engage said cylinder part and prevent unlocking movement thereof, said member being adapted to be moved by the key upon re-insertion of the same in the cylinder out of said engagement with the cylinder part.

6. In a lock, the combination of a key-cylinder, a pivotally mounted pawl adapted to be moved by a key in the cylinder into position to prevent unlocking movement of the cylinder, the pawl remaining in operative position when the key has been withdrawn from the cylinder and being adapted to be moved by re-insertion of the key in the cylinder to an inoperative position.

7. In a lock, the combination of a key-cylinder, a pivotally mounted pawl adapted to engage with said cylinder to prevent unlocking movement thereof, and a spring acting on said pawl, said pawl comprising a portion disposed in the path of movement of a key inserted in said cylinder so that said pawl is moved against the force of said spring into locking position with relation to the cylinder by the key during its rotative movement to lock the lock, said pawl being adapted to be released by longitudinal movement of the key upon re-insertion into the cylinder.

ROY D. KING.
